US0D1050628S

(12) **United States Design Patent** (10) **Patent No.:** **US D1,050,628 S**
(45) **Date of Patent:** **** Nov. 5, 2024**

(54) **LIVESTOCK SCRATCHING BRUSH**

(71) Applicant: **Shaoxing Jingyu E-commerce Co., Ltd.**, Zhejiang (CN)

(72) Inventor: **Meijuan Chen**, Zhejiang (CN)

(73) Assignee: **Shaoxing Jingyu E-commerce Co., Ltd.**, Shaoxing (CN)

(**) Term: **15 Years**

(21) Appl. No.: **29/955,779**

(22) Filed: **Aug. 3, 2024**

(51) LOC (14) Cl. **30-99**

(52) U.S. Cl.

USPC **D30/158; D30/159**

(57) **CLAIM**

The ornamental design for a livestock scratching brush as shown and described.

DESCRIPTION

FIG. 1 is a perspective view of a livestock scratching brush showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top plan view thereof;

FIG. 8 is bottom plan view thereof; and,

FIG. 9 is another changed perspective view thereof.

The broken lines depict portions of the livestock scratching brush and form no part of the claimed design.

1 Claim, 9 Drawing Sheets
